UNITED STATES PATENT OFFICE.

CORE H. REID, OF NIAGARA FALLS, NEW YORK.

FUEL-BURNING GRATE.

Application filed November 25, 1921. Serial No. 517,432.

To all whom it may concern:

Be it known that I, CORE H. REID, a citizen of the United States, residing at Niagara Falls, in the county of Niagara and 5 State of New York, have invented new and useful Improvements in Fuel-Burning Grates, of which the following is a specification.

This invention relates to fuel burning 10 grates.

An object of the present invention is to provide a grate of increased efficiency in fuel consumption.

A further object of the invention is to 15 provide a grate of universal character, readily adapted for use with coal of various sizes and grades.

A further object is to provide a grate especially adapted to be easily and economically repaired and maintained.

An improved embodiment of the invention illustrating the manner in which these and other objects are attainable is herein described and illustrated in the accompanying drawings, in which

Fig. 1 is a plan view of a portion of a grate from which certain elements have been in part removed to illustrate the underlying construction.

Fig. 2 is a vertical section transverse of the grate.

Figure 3 is an enlarged view of a modified form of one element.

Figure 4 is an enlarged section through one element.

The improved grate comprises a plurality of parallel units independently trunnioned in a supporting frame, each unit corresponding to a grate bar of the ordinary well known grate construction.

Each unit comprises a rectangular casting 1 of length equal to one dimension of the fire box and considerably less in width, so that a plurality of units assembled side by side will form a grate. The casting is provided with a plurality of openings 2 which may be rectangular in outline and should extend from edge to edge of the unit and be placed as near together as practicable, 45 allowing only for sufficient web between and surrounding the openings to impart sufficient strength to the grate. Surrounding each opening 2 is an upstanding flange 3, preferably tapering upward, with a vertical inner face and an outer face uniformly inclined upwardly and inwardly, as shown

at 4. A web 5 extends transversely across each opening, each web having a central bolt hole 6. A draft-directing and regulating cap 7 is provided for each opening 2. 60 Each cap comprises a casting corresponding in outline to the shape of the opening and having a rounded top 8 terminating in a depending flange or skirt 9 having a uniformly inclined inner face of angular slope 65 corresponding to the inclination on the face 4 of flange 3 and of a circumference to surround the flange. A supporting bolt 10 has its head cast in the under side of the cap, the bolt being adapted to be supported in the bolt hole 6 of the web to support the cap in place, by means of adjusting nuts 11 above and below the web. The cap may be so supported as to leave any desired air 70 passage between the skirt 9 and flange face 4. The web 5 is preferably depressed below the surface of the casting 1 to provide space for the upper adjusting nut 11 without unduly increasing the height of the flange and the length of the skirt. 75

A trunnion 12 projecting from the middle of each end of the unit provides for supporting the units in place in parallel relation in the furnace. The inner wall of the furnace or the fire box of the furnace may have an inwardly extending flange 13 on which the trunnion 12 rotatably rests. A retaining strip 14 clamped to the flange 13 by U-shaped bolts 15 embracing each trunnion will serve to hold the units in place. 80

Depending crank arms 16 on each unit provide for shaking or dumping the grate in the usual manner, details of which mechanism are not here shown.

Figure 3 illustrates a modification in which caps 7 are circular in outline. Otherwise, the construction is the same as that illustrated in Figures 1 and 2. The circular cap may present certain advantages in that there is less liability of ashes lodging against the cap in shaking or dumping the grate. However, consideration of space will in great measure determine the shape of the caps, it being desirable to provide for the necessary volume of air through the space between flange face 4 and skirt 9, without unduly reducing the strength of the unit. 100

It is to be noted that the units are arranged with adjacent edges in contact so 105 that no direct air passage through the grate is provided. Air supplied by forced draft 110

or otherwise will pass through the grate only by the path indicated by the arrows in Fig. 4. Therefore, there are no direct openings as in the old types of grate in common use. Such direct openings cause areas of rapid combustion immediately at the openings but cause areas of inferior combustion therebetween. The improved construction provides for the greatest possible diffusion of air throughout the entire fire bed. As the air passes through under skirt 9 it will be evenly diffused, some tending to follow along the surface of casting 1 and other portions tending to follow the surface of the caps. The result is that an extremely uniform distribution of air throughout is obtained and the efficiency of the grate is thereby increased. The volume of air may be readily predetermined by the adjustment of the nuts 11, whereby the air passage is uniformly increased or decreased.

With this improved grate it has been found that lower grades of fuel, such as screenings, etc., may be used with an efficiency in heating ton for ton equal to the efficiency ordinarily obtained from the larger sizes of coal.

Wear and burning may be compensated for by proper adjustment of the caps. Also, a burned out or broken cap may be readily replaced without scrapping the entire unit.

What I claim as new and desire to secure by Letters Patent of the United States is—

1. A fuel burning grate comprising a supporting member having openings, a flange surrounding each opening, a cap having a depending skirt surrounding each flange and providing an uninterrupted passage for air through the openings and between the flanges and skirts around the entire periphery of the openings.

2. A fuel burning grate comprising a supporting member having openings, a flange surrounding each opening, a cap having a depending skirt surrounding each flange and providing a passage for air through the openings and uninterrupted around the entire periphery of the openings between the flanges and skirts, and means for adjusting the caps to control the volume of air permitted to pass through said openings.

3. A fuel burning grate comprising a sup-

porting member having openings, a tapered flange surrounding each opening and a cap having a depending skirt conforming to the taper of said flange and surrounding each flange and providing a passage for air through the openings between the flanges and skirts uninterrupted around the entire periphery of the openings.

4. A fuel burning grate comprising a plurality of independently rotatable units, each unit comprising a supporting member having openings, a flange surrounding each opening, a cap having a depending skirt surrounding each flange and providing a passage for air through the openings and between the flanges and skirts.

5. A fuel burning grate comprising a plurality of independently rotatable units, each unit comprising a supporting member having openings, a flange surrounding each opening, a cap having a depending skirt surrounding each flange and providing a passage for air through the openings and between the flanges and skirts, and means for adjusting the caps to control the volume of air permitted to pass through said openings.

6. A fuel burning grate comprising a plurality of independently rotatable units, each unit comprising a supporting member having openings, a flange surrounding each opening, a cap having a rounded top and having a depending skirt surrounding each flange and providing a passage for air through the openings and between the flanges and skirts, and means for adjusting the caps to control the volume of air permitted to pass through said openings.

7. A grate bar comprising a casting having a plurality of openings, each opening surrounded by an upstanding tapered flange and traversed by a cap-supporting web, and a rounded cap co-operating with each opening, each cap having a depending skirt corresponding in outline to the upstanding flange and surrounding the same, each cap having adjustable supporting means for supporting the cap on the transverse web of the corresponding opening.

In witness whereof, I have hereunto subscribed my name.

CORE H. REID.
